UNITED STATES PATENT OFFICE.

CLIFFORD R. DUMBLE, OF ARLINGTON, MASSACHUSETTS, ASSIGNOR, BY MESNE ASSIGNMENTS, TO THE LAMSON COMPANY, OF BOSTON, MASSACHUSETTS, A CORPORATION OF MASSACHUSETTS.

SNAP SWITCH.

Application filed June 8, 1921. Serial No. 475,987.

To all whom it may concern:

Be it known that I, CLIFFORD R. DUMBLE, a citizen of the United States of America, and resident of Arlington, in the county of 5 Middlesex and State of Massachusetts, have invented new and useful Improvements in Snap Switches, of which the following is a specification.

This invention relates generally to a snap 10 switch and is particularly applicable for use in connection with devices in which a rotary movement is employed for the actuation of the switch, and in which it is desirable to effect either an open or closed circuit for a 15 certain period throughout a cycle of movements or operations.

One particular application of the switch is for use in connection with pneumatic tube 20 systems in which an electric motor is intermittently energized for a predetermined period either to exhaust the air from, or create pressure in, the system. Heretofore, the switches employed in this connection have been actuated by a gate or other part of the 25 pneumatic carrier system, and have depended upon a linear movement of a movable part of the system for the operation of the switch. Such an arrangement has necessitated the use of various crank and lever connections, whereas in the present instance the 30 switch may be directly and positively connected to and actuated by rotary movement of the gate bearing shaft, or other member movable when the carrier is inserted in the tube. In various installations it is at times necessary to mount the switch in different 35 relations, as for example in either a right-hand or a left-hand position, in which case it is desirable to have a switch operable by either a clockwise or a counter-clockwise 40 movement of the rotary actuator. Another desirable feature is to be able to vary the period through which the circuit is maintained or broken.

One of the objects of this invention is to provide a switch which will obviate the above objections, and afford the desirable results above noted.

Other objects of the invention are to provide 50 a switch which has few parts, which is simple in construction and durable in operation, which is economical to manufacture and is readily assembled, which is positive in action, which provides a quick make and

break, which provides a relatively wide 55 break at a plurality of points, which may be actuated by a rotary movement either continuously in either direction or alternately in opposite directions, which may be employed interchangeably under different 60 conditions, which is applicable for use in installations where a circuit is intermittently used for a certain period in a cycle of operations, which may be actuated by a relatively small movement and which has a certain 65 amount of free or lost movement, and in which a wiping or cleaning action is obtained between the contacts.

Other objects and advantages will be apparent from the following description and 70 the accompanying drawings in which,

Figure 1 is a top plan of the switch with the cover removed;

Fig. 2 is a bottom plan with the cap and actuator removed;

Fig. 3 is a longitudinal section on line 3—3 of Fig. 1;

Fig. 4 is a top plan of the support for the snap mechanism;

Fig. 5 is a side elevation of Fig. 4;

Fig. 6 is a top plan of the slide or carrier;

Fig. 7 is a side elevation of Fig. 6;

Fig. 8 is a longitudinal section on line 8—8 of Fig. 1;

Fig. 9 is a bottom plan of the switch with 85 the cap and insulating washer removed;

Fig. 10 is a longitudinal section of a modified form;

Fig. 11 is a side elevation showing an application of the switch to a pneumatic carrier tube.

The switch as shown includes a base 10, which may be formed of any suitable insulating material, and spaced terminals 11—12 mounted thereon. The base is preferably provided with suitable openings 13—14 through which conductors may be passed for attachment to the terminals. The terminals may be held in position by any suitable means, such for example as screws 15. Suitable contacts 16—17 may be provided which are connected to the respective terminals 12—13 on opposite sides of an aperture 18 through the base. One end 19 of each of the contacts may be inserted below the base 20 of the terminal, and held by the same screw which holds the terminal in place, one side 16' of the contact face being bent outward

at an angle to facilitate entrance of a co-operating movable contact.

The switch is of the snap type in which a quick make and break is provided. As shown, the mechanism for effecting the quick make and break action includes a slide or carrier member 21 which is mounted on a support 22 so as to be reciprocated thereon, the support being secured to the insulating base by screws 23. An arm 24 is provided having a bridging contact 25 mounted at one end thereof, the said contact functioning to complete the circuit between the terminal contacts 16-17. The mechanism for effecting the quick make and break action is adapted to be applied to the base as a unit.

The arm 24 is preferably pivotally supported at one end thereof on the reciprocating slide member 21, the arm being held upon its pivotal support by a spring 26, secured at one end to a pin 26' mounted therein, the other end being anchored or connected to the support 22 along the path of the carrier at a point preferably midway of the rest positions of the carrier, the purpose of such a relative arrangement of parts being to effect a quick snap action of the switch in making or breaking a circuit. The arm 24, the carrier or slide 21, and the support 22, on which the slide reciprocates, are formed of metal stampings.

The arm 24 is preferably U-shaped, having at its ends projecting ear portions 27 which are adapted to be seated in a suitable bearing 28 on the slide member 21. The other end of the arm is preferably provided with a forked or split portion 30 adapted to receive the bridging contact bar 25. The advantage of having the bridging contact 25 held within a forked structure is that the contact bar 25 is readily replaced, it being necessary merely to spread the fork portion to remove the bar 25, after which another one may be replaced and securely positioned by bending the forked portions about the bar. It is to be noted that no insulation is employed in mounting the contact bar 25 in the arm 24, and that a circuit between the terminal contacts is established directly through the contact bar 25, it being unnecessary that the circuit pass through a joint or connection of any character.

The support 22 is preferably formed with ears 31 through which screws may be threaded for securing the support to the insulating base 10. The support is provided at its ends with upwardly extending portions 32 which are so disposed as to function as stops for limiting the movement of the arm 24, the said portions also serving as abutments against which the arm may slide during the initial movement of the switch, prior to the snap action thereof. It is understood, however, that various other arrangements of

parts may be employed to affect the functions above noted. For example, a lug 33 (see Fig. 10) may be formed integral with the insulating base to function as a stop for limiting the movement of the arm 24 and as an abutment against which it may slide. A bridging piece 34 is provided centrally of the support to which piece one end of the spring 26 may be anchored or connected.

The slide or carrier member 21 is provided with a pair of upwardly extending spaced ear portions 28 on opposite sides of the slide which form bearings for the projecting lugs or ears 27 at the end of the U-shaped carrier arm. The slide 21 is provided with a slot 37 through which the spring 26 extends, thus permitting reciprocation of the slide without interference with the spring. Lateral displacement of the slide 21 relative to the support 22 is prevented by downwardly extending lugs 38-39, one pair being arranged at each end of the slide. For the purpose of preventing lateral displacement of the slide it would be sufficient that the length of the lugs should equal the thickness of the support. However, the lugs are extended a greater distance and cooperate with other mechanism to effect the reciprocation of the slide.

It is desirable to provide means for actuating the switch which may be operable by continuous rotary movement in either clockwise or counter-clockwise direction, or by alternate rotary movement in opposite directions. By providing an actuating means of this character, the switch may have numerous applications and may be employed in various relations and under different conditions. For example, in some applications, it is necessary to employ a switch in either a right-hand or left-hand relation. In the present switch, a simple and effective means is provided to meet the above conditions. An actuating member, rotatably supported, is adapted to be rotated continuously in either clockwise or counter-clockwise direction, or alternately in opposite directions, either of which movements alternately effects the opening and closing of the snap switch. The actuating means comprises a radially extending cam or finger 40 rotatably mounted in a removable cap or cover 41 for the switch. A stud 42 is rotatably mounted in a suitable bearing bushing 43 fixed to the cover or cap 41, the finger or cam 40 being fixed to the end of the stud so as to be movable therewith. When in assembled position, the rotation of the actuating member engages the downwardly projecting ears or lugs 38-39 of the slide member 21 for causing the reciprocation thereof, which in turn effects the movement or oscillation of the arm 24 about an axis transverse of the path of the slide and results in the snap action of the switch through the spring 26. The pairs

130

of downwardly extending lugs 38-39 are so positioned relative to the path of the finger or cam 40 that rotation of the finger 40 either clockwise or counter-clockwise will 5 actuate the slide 21. For example, if the actuator is rotated clockwise the engagement of the finger 40 and upper ear 39 (Fig. 9) will continue until the slide has been moved to a position in which the arm 24 is 10 past dead-center position, whereupon the spring 26 snaps the arm and slide to the other position of rest. If the arm 40 is rotated in a counter-clockwise direction (Fig. 9) it engages the lower lug 38 and likewise 15 throws the slide to the right.

The cap or cover 41 of the switch may be secured in position by any suitable means, such for example, as screws 44. The walls forming the passages 13, 14 through which 20 the wires are led to the contact terminals 11-12 extend below the surface of the insulating base 10 and serve as a guide and bushing in positioning the cap 41 upon the base 10 and also further prevents relative 25 movement therebetween. The cover 41 is preferably formed of metal and insulated from the finger or cam 40 and other metal parts of the switch by a washer 45 of insulating material between the cover 41 and the 30 base 10. The insulating washer 45 and an insulating sleeve 50' prevent the accidental short circuiting of parts of the switch of opposite polarity. By extending that portion of the base surrounding the openings 35 through which the conductors are carried, below the general level of the base, the use of separable bushings of insulation to protect the wires from accidental contact with the metal cap 41 is rendered unnecessary. 40 The entire switch may be enclosed by a suitable cover 51.

A snap switch of the above character may be contained in a relatively small space, and 45 may be employed generally as a snap switch for actuation by hand. In applying the switch to pneumatic tube carrier systems in which a motor is intermittently energized for a certain period, a switch of this character in which actuation is effected by a relatively small movement in one direction and permitting a relatively free movement in the same direction without affecting the operation 50 of the switch, is particularly desirable. For example, in dispatching a carrier 55 through a tube of a pneumatic system, the delivery end of the tube 47 (Fig. 11) is opened for reception of the carrier by raising a gate 48 a sufficient distance to permit the carrier to be inserted in the tube, after 60 which the end of the tube is again closed by returning the gate to its original position. In affecting the above operation, the gate 48 is rotated on its bearings 52 through a certain angle, which movement will rotate the 65 shaft 53 sufficiently to actuate the switch.

In assembling the switch, the support 22, the carrier or slide 21, the arm 24 and the spring 26 may be placed in their proper relative positions, these assembled parts constituting a unit which may be placed in the 70 insulating base 10 in proper relative position with respect to the stationary terminal contacts 16-17 arranged on the base. It is to be noted that the spring 26 serves to maintain the arm 24 in its bearing 28 upon 75 the reciprocating slide 21, and also holds the slide 21 in position upon the support 22 as it is reciprocated thereon. The inclined upper part of the upwardly extending portion 32 functions as a stop for the oscillating arm 24 and the lower portion functions 80 as a stop for the slide 21.

One advantage of the relative arrangement of the terminal contacts 16-17, with 85 respect to the movement of the bridge contact or bar 25 and the mechanism effecting the movement thereof, is that the movement of the carrier and bridging contact 25 is in a plane intermediate the terminal contacts so that a wiping action between the bridging contact and the face of the terminal contacts is obtained, the effect of which is to maintain a good contact and to keep the contact surfaces free from dust and other 90 foreign matter. A further advantage of such arrangement is that a double break in the circuit is simultaneously effected by a snap action. It is to be noted that the sliding or wiping action of the contact bar upon the faces of the terminal contacts is not confined to the same path or surface when the circuit is made as it is when broken. When 95 the contact is established, the wiping action is effected as the contact bar is on its quick snap downward movement which is on the latter part of the path traversed by the contact bar in its movement from one position to the other, whereas when the circuit is broken the wiping action is effected by relatively slow upward movement of the contact 100 bar through the first portion of the path traversed by the contact bar. A further advantage of such an arrangement is that the wear is distributed over a wider area, thus 105 prolonging the life of these parts of the switch. 110

A switch of this character may be readily employed to control a plurality of circuits. This may readily be accomplished by providing a second pair of terminal contacts, such as 50 (Fig. 10) disposed at the opposite sides of the switch base in a position corresponding to that occupied by the first pair of contacts. Separate terminals would 120 of course be provided for the respective contacts. By the employment of two pairs of terminal contacts, one circuit would be interrupted and another circuit would be established. 125

The insulating sleeve 50' insulates shaft 130

42 from journal 43 so that the switch casing is effectively protected from the internal metallic mechanism.

By employing an insulating connector 61 5 between the metallic shafts 42 and 53 the internal metallic mechanism can not become grounded on the metallic casing through the shafts.

I claim:

- 10 1. Switch mechanism of the class described comprising a pair of oppositely disposed terminals, a V-shaped oscillatable arm having a slot in its closed end, a contact bar removably secured in said slot, and means 15 for imparting oscillatory movement to the arm whereby simultaneously to move the opposite ends of said bar into or out of contact with the respective terminals.
- 20 2. Switch mechanism comprising a pair of spaced, oppositely disposed terminals, a metallic lever arm pivotally mounted for oscillation in the space between said terminals, said arm having a recess in its free extremity, and a bar seated in said recess, and 25 held therein by pressing the material of the arm inwardly over the bar, said bar being so constructed and arranged as simultaneously to contact with the respective terminals upon proper movement of the arm.
- 30 3. A snap switch comprising a pair of spaced terminals, a U-shaped arm pivotally supported at its open end to oscillate in a plane between said terminals, the closed end of said arm being bifurcated to form a recess, a contact bar seated in said recess and 35 projecting to opposite sides of the arm, and means for imparting movement to the arm whereby simultaneously to move the opposite ends of said bar into and out of contact 40 with the respective terminals.
- 45 4. A snap switch comprising an elongate base plate, a carrier slidably thereon, a pair of stops projecting upwardly from opposite end portions of the base plate, an arm having one end pivotally secured to the carrier and provided with contact means mounted upon its opposite end, a spring having one end secured to an intermediate point in said arm and at its opposite end to the central 50 part of the base, and rotatable means for slidably moving said carrier whereby to swing said arm from engagement with one of said stop members into engagement with the other.
- 55 5. A switch comprising a base plate having an integral stop member upstanding from opposite ends thereof, a carrier slideable upon said base plate, lugs projecting downwardly from said carrier and embracing the base plate whereby to position the carrier relatively thereto, an arm pivotally secured to the carrier and alternatively engageable with the aforesaid stops, and means 60 for slidably moving the carrier.
- 65 6. In a snap switch of the type having a

circuit terminal and a movable contact adapted to be moved into and out of contact with the terminal, snap mechanism comprising a carrier or slide movable to and fro between positions of rest, an arm pivoted on the carrier to swing about an axis transverse of the path of the carrier between positions of rest, said contact being disposed on said arm so as to engage said terminal when the arm is in one position of rest, an anchor disposed along the path of the slide, a spring interposed between the arm and anchor to snap the arm and slide, when moved part way from one position of rest into the other position of rest, and rotatable means engageable with an element of the carrier for reciprocating the latter.

7. In a snap switch of the type having a circuit terminal and a movable contact adapted to be moved into and out of contact with the terminal, snap mechanism comprising a carrier or slide movable to and fro between positions of rest, an arm pivoted on the carrier to swing about an axis transverse of the path of the carrier between positions of rest, said contact being disposed on said arm so as to engage said terminal when the arm is in one position of rest, an anchor disposed along the path of the slide, and a reversibly rotatable actuator engageable with an element of said carrier upon rotation thereof in either direction to move the carrier from either position of rest to a position where it is snapped to the other position of rest by said spring.

8. In a snap switch of the type having a circuit terminal and a movable contact adapted to be moved into and out of contact with the terminal, snap mechanism comprising a carrier movable to and fro between positions of rest, an arm pivoted on the carrier to swing about an axis transverse of the path of the carrier between positions of rest, said contact being disposed on said arm so as to engage said terminal when the arm is in one position of rest, an anchor disposed along the path of the carrier, and a rotary actuator engageable with said carrier to move the carrier from one position of rest to a position where it is snapped to the other position of rest by said spring, the snap movement carrying the carrier into position to be engaged by the actuator for return to the first position when the actuator is rotated in either direction.

9. In a snap switch of the type having a circuit terminal and a movable contact adapted to be moved into and out of contact with the terminal, snap mechanism comprising a carrier movable to and fro between positions of rest, an arm pivoted on the carrier to swing about an axis transverse of the path of the carrier between positions of rest, said contact being disposed on said arm so as to engage said terminal when the arm is in

- one position of rest, an anchor disposed along the path of the carrier and a rotary actuator for actuating said carrier, the actuator being rotatable about an axis intersecting the path of the carrier and having a radial arm, and the carrier having shoulders arranged in the path of said arm so that the carrier may be moved from either position of rest into position where it will be snapped to the other position of rest by rotating said actuator in either direction, said arm engaging different shoulders depending upon the direction in which it is rotated to move the slide in the same direction. 5
- 10 15 10. A switch comprising a carrier movable to and fro, a U-shaped integral arm pivotally mounted at its open end on said carrier to swing about an axis transverse of the path of the carrier, a coil spring interconnecting said arm with an anchor disposed along the path of movement of said axis so that the spring snaps the arm back and forth as the axis passes the anchor in the to-and-fro movement of the carrier, a pair of terminals adjacent the path of said arm, and a removable contact member carried by the closed end of said arm and comprising elements simultaneously engageable with the respective terminals when the arm is snapped to one side. 20 25 30
11. A switch comprising a fixed terminal contact, an oscillatory contact engageable therewith, a reciprocable slide carrying said movable contact, and means including a rotary actuator for actuating said slide by a continuous rotary movement of the actuator in either direction. 35
- 40 12. A switch comprising a terminal contact, a movable contact, a carrier for moving said movable contact into and out of engagement with said terminal contact, an actuator adapted for continuous movement either clockwise or counter-clockwise and also for alternate clockwise and counter-clockwise movement, and cam means for transmitting movement from said actuator to said carrier whereby to move the carrier alternately into open and closed circuit positions on any of said movements of the actuator. 45 50
- 55 13. A snap switch comprising a base plate, a carrier slidable thereon, elements projecting from said carrier and engaging said base plate whereby to position the carrier relatively to the base plate, lugs projecting from one face of the carrier and providing bearings, an arm pivotally supported in said bearings, a tension spring connecting said arm with the central part of the base plate, and means for slidably moving the carrier. 60 65
14. A snap switch comprising an elongate base plate, a carrier slidable thereon, contact means mounted upon the carrier, lugs projecting from the carrier and engaging opposite edges of the base plate whereby to guide the carrier in its movements, and a rotatable cam device engageable with said lugs for imparting reciprocatory sliding movement to the carrier. 70
15. A switch comprising an elongate guide member, a carrier slidably engaging the same, said carrier having a pair of lugs projecting from one face thereof and a cam rotatable in a plane substantially parallel with the plane of movement of the slide member and engageable with said lugs for imparting reciprocatory movement to the carrier. 75
16. A switch comprising circuit closing contacts, means for alternately opening and closing said contacts, said means including a reciprocable member, an actuator rotatably mounted, and means arranged between the actuator and the reciprocable member for alternately opening and closing the contacts by rotary movement of the actuator either continuously in either direction or alternately in opposite directions, said last named means including a plurality of pairs of ears movable with the reciprocable member and a finger rotatable with the actuator. 80 85 90
17. A switch comprising circuit closing contacts, means for alternately opening and closing said contacts, said means including a reciprocable member, an actuator rotatably mounted, and means including a plurality of pair of ears movable with the reciprocable member, a finger movable with the actuator and adapted to cooperate with the ears for effecting the operation of the contacts, said ears being spaced from each other and arranged in pairs on opposite sides of the reciprocable member, said finger being arranged to alternately cooperate with each one of a pair of ears on one side of the reciprocable member when the actuator is alternately rotated in opposite directions for effecting the opening and closing of the switch and to cooperate with one ear of each pair disposed on opposite sides of the reciprocable member when the actuator is rotated continuously in either direction. 95 100 105 110
18. In a snap switch of the type having a circuit terminal contact and a movable contact, snap mechanism including a reciprocable carrier for moving the movable contact into and out of engagement with the terminal contact, a plurality of pairs of projections arranged on the carrier in rectangular form, one pair being disposed on each side of the carrier, an actuator rotatably mounted, and a finger movable with said actuator arranged to alternately cooperate with each of one pair of projections when said actuator is moved alternately in clockwise and counter-clockwise direction to effect the reciprocation of the carrier, and to successively cooperate with one of each pair of projections on opposite sides of the carrier when said 115 120 125 130

actuator is rotated continuously in either direction to effect the reciprocation of the carrier.

19. In a snap switch including a pair of contacts one of which is movable, snap mechanism for opening and closing said contacts including a reciprocating slide, an actuator rotatably mounted for reciprocating said slide, a plurality of ears projecting from said slide and arranged in spaced relation thereon, and a finger rotatable with said actuator adapted to alternately cooperate with adjacent ears when the actuator is rotated alternately in opposite directions to effect successively the opening and closing of the contacts by reciprocation of the slide.

20. In a snap switch including a pair of contacts one of which is movable, snap mechanism for opening and closing said contacts including a reciprocating slide, a support on which said slide reciprocates, an actuator for the slide rotatably mounted, means for guiding the slide on the support including two pairs of ears arranged in rectangular form, one pair being spaced on opposite sides of the slide, said actuator having a finger rotatable therewith adapted to alternately engage one of each pair of ears on one side of the slide when rotated alternately in opposite directions, and to alternately engage ears diagonally disposed from each other when the actuator is rotated continuously in either direction for effecting the opening and closing of the contacts.

21. In a switch having a pair of contacts, snap mechanism for effecting the opening and closing of the contacts including a reciprocating slide having a pair of downwardly projecting ears on each side thereof, a support between said ears on which the slide reciprocates, means for limiting the movement of the slide, and an actuator rotatably mounted adapted to cooperate with the slide to reciprocate the same by rotary movement either alternately in opposite directions or continuously in either direction, said actuator including a radially extending finger adapted to be rotated between said pairs of ears whereby when the actuator is rotated alternately in opposite directions the finger will alternately engage each one of a pair of ears on one side of the slide, and when the actuator is rotated continuously in either direction the finger will alternately engage one of each pair of ears on opposite sides of the slide, said ears being diagonally disposed from each other.

22. A switch comprising guide means, a carrier slidably engaging said guide means, a contact member movable with the carrier, two pairs of spaced elements projecting from the carrier, and a cam rotatable in a plane substantially parallel to the plane of movement of the carrier, said cam being constructed and arranged to engage the ele-

ments of one pair upon rotation in one direction, and the elements of the other pair upon rotation in the other direction, whereby to impart reciprocatory movement to the carrier.

23. In a snap switch including a plurality of contacts one of which is movable and snap mechanism for said movable contact, means including an actuator for imparting to said snap mechanism rotary movement alternately in opposite directions or continuously in either direction, said means comprising a sliding carrier having two pairs of projecting ears spaced and arranged parallel to each other in pairs so as to form a parallelogram, said actuator being mounted to rotate about an axis passing through the path of said carrier, and a radially extending finger movable with the actuator and adapted to alternately engage each one of a pair of ears on one side of the parallelogram when said actuator is rotated alternately in opposite directions, said finger being adapted to successively cooperate with one of each of the pairs of ears, said ears being diagonally disposed from each other when said actuator is rotated continuously in either direction.

24. A switch comprising an insulating base having opening therein for the passage of conductors, annular projecting flanges surrounding said openings, switch mechanism mounted upon said base, a cover plate having openings for the passage of the respective flanges whereby the cover plate is positioned relatively to the base, and means for securing the cover plate to the base.

25. A snap switch comprising in combination, a plurality of contacts, one of which is movable, an arm for said movable contact, and snap mechanism for said movable contact, said snap mechanism including a slide having a pivotal support for one end of said arm, stops limiting the movement of the slide in each direction, a spring having one end secured to the arm and the other end fixed at a point approximately midway between the stops whereby said movable contact is snapped into and out of engagement with the other contact upon reciprocation of the slide, means including an actuator rotatably mounted for reciprocating said slide by rotary movement either alternately in opposite directions or continuously in either direction, said last-named means including two pairs of projecting ears arranged upon the slide to form a parallelogram, said actuator being rotatable about an axis passing between the sides of the parallelogram formed by said ears, and a finger movable with said actuator adapted to cooperate with the ears for effecting the reciprocation of the slide when said actuator is rotated alternately in a clockwise and counter-clockwise direction or continuously in either a clockwise or counter-clockwise direction.

26. In a snap switch of the character described having a plurality of contacts, one of which is movable, and snap mechanism cooperating therewith, means including a
5 rotary actuator for alternately effecting the opening and closing of said contacts by either a rotary movement alternately in opposite directions or continuously in either direction, said means comprising a support
10 having stops thereon, a slide adapted to be reciprocated upon said support between said stops, two pairs of ears extending downwardly from said slide, one pair of ears being arranged on opposite sides of said slide
15 and serving as guides for maintaining said slide in proper position upon the support, the said ears being arranged substantially in the form of a parallelogram, and a radially extending finger carried by said rotary actuator adapted to cooperate with said ears 20 for effecting the reciprocation of said slide when said actuator is rotated alternately in opposite directions or continuously in either direction, the axis about which said actuator rotates passing through a point intermediate the sides of the parallelogram and approximately midway between the stops limiting the movement of the slide.

Signed by me at Boston, Massachusetts, this twenty-fourth day of May, 1921.

CLIFFORD R. DUMBLE.
